(57) **CLAIM**

The ornamental design for a wallet/key chain unit including long-range and short-range communications circuitry for a smartphone and vehicle, as shown and described.

DESCRIPTION

FIG. 1 is a perspective view of the wallet/key chain unit including long-range and short-range communications circuitry for a smartphone and vehicle;

FIG. 2 is a perspective view of the wallet/key chain unit including long-range and short-range communications circuitry for a smartphone and vehicle;

FIG. 3 is a straight-on view of the wallet/key chain unit including long-range and short-range communications circuitry for a smartphone and vehicle;

FIG. 4 is a bottom edge view of the wallet/key chain unit including long-range and short-range communications circuitry for a smartphone and vehicle

FIG. 5 is a top edge view of the wallet/key chain unit including long-range and short-range communications circuitry for a smartphone and vehicle;

FIG. 6 is a left edge view of the wallet/key chain unit including long-range and short-range communications circuitry for a smartphone and vehicle

FIG. 7 is a straight-on view of the wallet/key chain unit including long-range and short-range communications circuitry for a smartphone and vehicle; and,

FIG. 8 is a right edge view of the wallet/key chain unit including long-range and short-range communications circuitry for a smartphone and vehicle.

The broken lines showing a portion of the wallet/keychain are for the purpose of illustrating environment and form no part of the claimed design.

1 Claim, 3 Drawing Sheets
